POST-OPERATION BELT

Caroline A. Muller, Minneapolis, Minn.

Application May 24, 1948, Serial No. 28,890

2 Claims. (Cl. 128—171)

1

This invention relates to a belt and particularly to a belt constructed and arranged to be worn by patients in a hospital and particularly after having had an abdominal operation or after a child birth.

It has been the practice in hospitals to cover the wound or incision after an operation and one common method of holding the covering in place is to use adhesive tape extending across the covering and adhering to the skin of the patient. The adhesive from the tape adheres to the skin and it is sometimes painful to have the tape removed from the skin. Bandages extending about the body are seldom used as it is too inconvenient to remove them to examine the wound or incision.

It is an object of this invention to provide a simple and efficient belt which can be comfortably and conveniently worn by the patient to hold the covering of the incision or wound in place or to restore and hold the body in shape after a child birth.

It is a further object of the invention to provide a belt adapted to be worn after an operation, said belt comprising a strip of strong fabric of a width to cover the abdomen, said belt extending about the body of the patient, having a plurality of fastening means at the front thereof, said belt having a smooth inner side and preferably having spaced stiffening means at its outer side particularly at the ends and at the rear thereof.

It is further an object of this invention to provide a post-operation belt adapted to extend about the abdominal part of the wearer's body to hold the wound covering in place, said belt having a plurality of fastening means at its front including straps and a plurality of buckles cooperating therewith, said buckles being readily detachable from said belt so that said belt can be laundered.

These and other objects and advantages of the invention will be fully set forth in the following description made in connection with the accompanying drawings in which like reference characters refer to similar parts throughout the several views and in which:

Fig. 1 is a view in front elevation of the belt in operative position on the body of the wearer;

Fig. 2 is a rear view of the belt shown in Fig. 1;

Fig. 3 is a view in elevation of the rear side of the belt in extended form;

Fig. 4 is a plan view of a buckle used; and

Fig. 5 is a partial horizontal section taken substantially on line 5—5 of Fig. 1, as indicated by the arrows.

2

Referring to the drawings a structure of belt is shown comprising a strip of fabric 10. Said strip will be made of strong flexible fabric, such as light canvas or similar material. While the exact shape of the belt might vary in practice, in the embodiment of the invention illustrated strip 10 is shown as having slightly curved convex substantially parallel sides, as shown in Fig. 3. Said strip 10 will preferably have a hem or double thickness 10a and 10b at either side thereof held by stitching 10d, the edges of strip 10 being turned outwardly, as shown in Figs. 1, 2 and 3. Stiffening means 11 are provided at the rear of the belt, the same extending transversely thereof in slightly diverging or substantially parallel relation, said stiffening means being made of superposed layers of fabric stitched to the strip 10. Said stiffening means are thus very flexible and foldable. Stiffening means 12 are provided at the ends of strip 10 and these may be of the same character as the stiffening means 11. A flap 13 is secured to one end of the strip 10 and to one of the stiffening means 12. A plurality of straps 14 are provided, said straps being disposed in equally spaced relation transversely of strip 10 and secured to one end of strip 10. At the other end of said belt a plurality of loops 15 are secured in spaced relation to the end of strip 10 and a buckle 16 is secured in each of said loops. Buckle 16 has a substantially rectangular frame with a movable bar 16a thereon being toothed or corrugated at one side to cooperate with a toothed or corrugated portion 16b on one end portion of said buckle. Buckle 16 has at one side, portions 16c having an opening 16d therebetween, portions 16c extending parallel to one end member 16e of said buckle. The portions 16c are disposed in the fabric loops 15.

In operation, after the patient has had his operation and the covering is applied to the wound or incision, the belt will be placed around the body of the wearer and over the said covering, the straps 14 being engaged in the buckles 16 and the belt drawn to snug position. Straps 14 will be engaged by bar 16a against the teeth or corrugations 16b so as to be held in stationary position with the belt closed. The straps and buckles will overlie the flap 13 which will extend between the ends of the belt and beneath the same in contact with the body of the wearer. The stiffening means and portions of increased thickness 10a and 10b will be disposed at the outer side of the belt so that the inside of the belt is quite smooth. The belt holds the covering of the wound in place so that it will not move or shift and the belt also holds the abdominal

part of the patient in rather definite form so that there is no tendency to displace the covering. The belt really adds to the comfort of the patient. In order that the belts may be readily laundered, as will be necessary in a hospital, the buckles 16 are constructed so that the can be readily detached. The buckles can be very quickly and easily detached from the loops 15 by moving the edge of each loop through the opening 16d. The buckles can likewise be very readily placed in position by moving the edges of the loops through the openings 16d so that portions 16c engage the inside and end of said loops. The belt also has great utility after cases of child birth. It is desirable to restore and hold the abdominal part of the body in normal shape. The present belt has proven exceptionally efficient for this purpose and eliminates the necessity for binding with bandages or strips. The belt can be nicely adjusted to bring the body to the desired form.

From the above description it will be seen that I have provided a novel, simple and very efficient device to be used for patients after having had an operation. The device fills a long felt want and is being enthusiastically received by surgeons and hospital staffs. The use of the device eliminates the necessity for the adhesive tape. The wound can be very quickly examined by merely opening the belt by releasing the straps 14. The wound is protected and the covering kept in better shape than when the adhesive tape was used, as the belt holds the abdominal part of the body in definite form and prevents wrinkling due to movements of the patient.

The device has been amply tested in actual practice, found to be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An abdominal belt for holding a wound covering in place after an abdominal operation comprising an elongated continuous strip made of a single thickness of strong white flexible non-

elastic canvas fabric, said strip having a width to extend over the abdomen of the wearer and substantially to the crotch, said strip having curved substantially parallel sides, a narrow strip 5 of foldable fabric extending across one end of said strip and stitched thereto, spaced loops stitched to said end extending longitudinally of said first mentioned strip, removable buckles having a portion received in said loops and readily 10 removable therefrom, a second narrow strip extending across said first mentioned strip spaced from the other end thereof and stitched thereto, spaced straps extending longitudinally of said first mentioned strip stitched to said second strip 15 and adapted to cooperate with said buckles respectively and a plurality of spaced strips of foldable fabric at the rear and central portion of said first mentioned strip extending transversely thereof, said narrow strips and plurality of strips being disposed at the outer side of said first mentioned strip so that the inner side of said first mentioned strip is smooth whereby said belt can conform to the wearer's body and bind it tightly against excessive movement so that 20 said wound covering will be held securely in place and said buckles may readily be removed so that said belt can be laundered.

2. The structure set forth in claim 1, said belt having stitched hem at its longitudinal edges, 30 the edges of said first mentioned strip being at the outer side thereof and said plurality of narrow strips diverging downwardly.

CAROLINE A. MULLER.
